US00D596704S

(12) **United States Design Patent**
Born et al.

(10) **Patent No.:** US D596,704 S
(45) **Date of Patent:** ** Jul. 21, 2009

(54) **DISPENSER CARTRIDGE**

(75) Inventors: **Jason Alan Born**, Loveland, OH (US);
David James Emmons, Plymouth, MN (US);
Johannes Nikolai Gaston, Minnetonka, MN (US); **Douglas James VanOrnum**, Minnetonka, MN (US);
Dominic James Daunter, Howell, MI (US); **Noah Eberhard Dingler**, Waterford, MI (US)

(73) Assignee: **PuR Water Purification Products, Inc.**, Cincinnati, OH (US)

(**) Term: **14 Years**

(21) Appl. No.: **29/321,501**

(22) Filed: **Jul. 17, 2008**

(57) **CLAIM**

The ornamental design for a dispenser cartridge, as shown and described.

DESCRIPTION

FIG. 1 is a perspective view of a dispenser cartridge illustrating our new design;

FIG. 2 is a left side elevational view of the design of FIG. 1; FIG. 3 is a right side elevational view of the design of FIG. 1; FIG. 4 is a front side elevational view of the design of FIG. 1; FIG. 5 is a back side elevational view of the design of FIG. 1; FIG. 6 is a top planar view of the design of FIG. 1; and, FIG. 7 is a bottom planar view of the design of FIG. 1.

Undisclosed visible surface(s)/portion(s) of the article not forming part of the claimed design.

The broken line showing of a pitcher is included for the purpose of illustrating and forms no part of the claimed design.

1 Claim, 6 Drawing Sheets
